UNITED STATES PATENT OFFICE.

ARTHUR C. FERGUSON, OF BROOKLYN, NEW YORK.

PRINTER'S BLANKET.

SPECIFICATION forming part of Letters Patent No. 680,577, dated August 13, 1901.

Application filed January 10, 1900. Serial No. 994. (No model.)

To all whom it may concern:

Be it known that I, ARTHUR C. FERGUSON, a citizen of the United States, residing at Brooklyn, in the county of Kings and State 5 of New York, have invented certain new and useful Improvements in Printers' Blankets; and I do hereby declare the following to be a full, clear, and exact description of the invention, such as will enable others skilled in 10 the art to which it appertains to make and use the same.

This invention relates to beds or blankets for the platens of printing-presses; and it consists, substantially, in such features of improvements as hereinafter more particularly 15 pointed out.

The invention has for its object to provide means for producing impressions from type and stereotype forms without the necessity of 20 resorting to the ordinary "make-ready" process by which to overcome inequalities in the surface of the bed or form. It has been proposed in many instances heretofore to overcome these objections in various ways; but I 25 propose by the present invention to do so much more successfully than has hitherto been accomplished in many instances.

In carrying my invention into effect I provide one or more sheets or strips of wire- 30 gauze of very fine mesh, one overlapping the other, and above the uppermost one I place a sheet or strip of very fine material having suitable resiliency—such, for instance, as fine steel or gutta-percha. This body I arrange 35 beneath the ordinary blanket employed upon the platen of a bed of a flat or cylinder press, and while this body is capable of conforming to the general shape of the platen or cylinder it also possesses sufficient elasticity and 40 resiliency to meet or overcome any of the inequalities of the surface of an ordinary printing-bed. It is well known that inequalities of printing are alone produced by the inequalities of the printing-surface, and this I 45 propose to overcome in the safest and most expeditious manner. At the same time I have not lost sight of the fact of the desirability of cheapness and ease of manipulation with which such devices should be handled, 50 and it will be found from the description hereinafter following that my invention possesses all of the qualities which go to make

up durability, effectiveness, and other desiderata. In other words, my invention is intended to supply a long-felt want in the 55 printer's trade, and one which will enable much more accurate work to be accomplished than has been accomplished heretofore in many instances irrespective of the number of devices in use for the same purpose. 60

I can accomplish my invention in several different ways, but preferably I arrange two or more sheets of the gauze, one overlapping the other, in such manner that the threads or plies of the one sheet will cross the spaces of 65 the adjacent one, while the thin sheet of gutta-percha or steel may be laid thereon in any suitable manner. In order to secure the parts together, I preferably stitch them at the edge in such manner that the stitching will 70 lie flush or below the surface of the device. In some cases I may only stitch the blanket at the edges, or in other cases I may stitch the same at the edges and through intermediate portions of the body thereof. These 75 parts of my invention, however, it will be understood, are immaterial, since the same may be united in any suitable way.

I will now refer to my invention in detail in order that a more perfect description may 80 be had thereof, reference being had to the accompanying drawings, in which—

Figure 1 is an enlarged view of a portion of my improved blanket, the same showing but a single sheet of wire-gauze together with a 85 covering or sheet of thin steel or gutta-percha, the said view also showing the tympan of the platen broken away. Fig. 2 is a similar view showing two sheets of wire-gauze, one overlaid upon the other, with the addition of the 90 thin sheet of steel or gutta-percha. Figs. 3 and 4 are sectional views in detail of the preceding figures, respectively. Fig. 5 is a view in detail showing the manner of stitching the edges of the wire-gauze and the thin steel or 95 gutta-percha. Fig. 6 is a view showing my device as applied to an ordinary cylinder-press, the ordinary tympan in this instance being also shown.

While my invention is capable of comparatively short reference or description, the uses to which it may be put are almost unsurpassed in the printing trade or art, and I will simply refer to the same in as detailed a manner as

is necessary to a full and complete understanding of the same by the public.

5 A represents a sheet of wire-gauze, which, as shown in Fig. 1, is overlapped by a thin sheet of steel or gutta-percha or other material B, having suitable resiliency, which in turn is covered by the ordinary tympan D.

10 As is well known in the art of printing, the slightest protrusion of a type from the printing bed or surface will produce most undesirable effects on the paper or other sheet printed upon, whereas by having a suitable elastic and resilient blanket, as herein shown, beneath the ordinary printers' tympan such 15 irregularities are overcome. The purpose has been heretofore to obtain a surface which would compensate for the slightest irregularity of the printing-surface and which with but one or two exceptions has been unable to 20 be accomplished. By the use of my device all such irregularities are overcome, and no matter how minute the imperfection of surface may be when the platen is brought against the printing-face the whole surface of the latter 25 will be flattened out, and perfect results thereby secured.

20 In Fig. 2 I have shown the preferred form of my device, and wherein A' A' each represent a sheet of wire-gauze or like material, 30 one being laid upon the other and the surface of the uppermost one being overlaid by a thin sheet of steel or gutta-percha B', which in turn is covered by the ordinary tympan D. The wires of the gauze or reticulated member 35 comprise elongated rectilinear horizontally-separated elements which when superposed contact with each other at only such points as are unsupported by elements below, and consequently resiliently yield under pressure. 40 In this construction and arrangement it will be seen that the longitudinal and transverse wires of one gauze sheet are made to cross the intermediate spaces of the other sheet and from which I obtain the very best results, 45 due to the fact that every bit of available surface of the device is rendered effective to the ends desired. Inasmuch as the gauze sheets are finely woven it is much easier to effect the desired crossing of the sheets by arranging 50 the wires of one sheet at an angle to the other, as shown in Fig. 2.

55 In Fig. 5 I have shown how the gauze sheet or sheets A and the gutta-percha sheet B are secured together at the edges in any suitable way, as by stitching, (indicated at H.) In order that the said stitches shall not protrude above the surface of said sheet B, the latter is grooved, as shown at H', the stitches lying in the bottom of said groove.

60 In Fig. 6 I have shown my device as applied to a cylinder J of an ordinary cylinder-press, and which will be understood without further reference.

65 From the foregoing it will be seen that my invention in all of its arrangements comprehends the same general feature or element of improvement—that is to say, one having suit-

able elastic and resilient body throughout with no intermediate inelastic portions, and one in which the platen is at all times met by an 70 elastic surface, which straightens out or puts into place any inequalities of surface thereof produced by the protrusion of type or other causes. It will be seen that my invention also comprehends the features of simplicity, 75 combined with durability, ease of application, as well as cheapness, ease of repair, and ready accessibility. It will further be seen that uniform impressions can be made from 80 type or stereotype forms without the previous preparation of the make-ready process so frequently necessary in the ordinary printing operations.

85 The materials comprising my device are easily obtainable, thereby making a saving in expense, and while I have specified wire-gauze and sheet-steel or gutta-percha as the elements employed it is evident that any equivalent thereto is intended to be included within my invention. I do not wish to be 90 understood, furthermore, as confining myself to the manner of joinder of the several parts, since I may find it convenient to cement the sheets together or else rivet them or in some other manner join them in an 95 equivalent way to that herein shown and described.

100 Therefore, without limiting myself to the precise details of construction herein shown and described, I claim—

1. A bed or surface for the platens of printing-presses, the same comprising two or more sheets of wire-gauze laid one upon the other, with the wires of one sheet crossing the intermediate spaces of the other sheet, and an 105 outer sheet of elastic material, substantially as described.

2. A bed or surface for the platens of printing-presses, the same comprising two or more sheets of wire-gauze laid one upon the other, 110 with the wires of one sheet disposed at an angle to those of the other sheet, and an outer sheet of elastic material, substantially as described.

3. A bed or surface for the platens of printing-presses, the same comprising two or more sheets of wire-gauze laid one upon the other, 115 with the wires of one sheet disposed at an angle to those of the other, an outer sheet of elastic material, and means for fastening all 120 of said sheets together, substantially as described.

4. A bed or surface for the platens of printing-presses, the same comprising two or more sheets of wire-gauze laid one upon the other, 125 with the wires of one sheet disposed at an angle to those of the other, an outer sheet of elastic material grooved in its upper surface at the edges, and fastening devices lying in said grooves for securing all of said sheets 130 together, substantially as described.

5. A bed or surface for the platens of printing-presses, the same comprising two or more sheets of wire-gauze laid one upon the other,

with the wires of one sheet disposed at an angle to those of the other, an outer sheet of elastic material grooved in its upper surface at the edges, and stitching passing through 5 the bottom of the grooves for securing all of said sheets together, substantially as described.

6. A bed or surface for the platens of printing-presses, the same comprising a wire-gauze material, and an outer elastic material, the latter being grooved in its outer surface near the edges, and a stitching lying in the bottom of the grooves for securing the parts together, substantially as described.

15 7. An impression member constituted by a multiplicity of elongated rectilinear, horizontally-separated elements contacting with each other at only such points as are unsupported by elements below, and a bridging- 20 plate thereon.

8. An impression member constituted by a plurality of sets of reticulated wires adapted by their superposition to resiliently yield under pressure, and a bridging-plate thereon.

9. A make-ready comprising an elastic member 25 and a member formed of wires arranged in a plurality of plies one of which plies is located to bring its wires between the vertical planes occupied by the wires of another ply.

10. A make-ready comprising an elastic 30 member and a member formed of wires arranged in a plurality of plies one of which plies intersects the spaces between the wires of the other ply.

In testimony whereof I affix my signature 35 in presence of two witnesses.

ARTHUR C. FERGUSON.
